UNITED STATES PATENT OFFICE.

ELGIN COURT MAY, OF EDMONTON, ALBERTA, CANADA.

DESIGN FOR A VEHICLE WHEEL-TIRE.

47,890.

Specification for Design.

Patented Sept. 28, 1915.

Application filed August 16, 1915. Serial No. 45,829. Term of patent 3½ years.

To all whom it may concern:

Be it known that I, ELGIN COURT MAY, a subject of the King of Great Britain, residing at Edmonton, in the Province of Alberta and Dominion of Canada, have invented a new, original, and ornamental Design for Vehicle Wheel-Tires, of which the following is a specification, reference being had to the accompanying drawing, forming part thereof.

The drawing is a perspective view of a vehicle wheel tire showing my design.

I claim:

The ornamental design for a vehicle wheel tire substantially as shown.

In testimony whereof, I have hereunto subscribed my name.

ELGIN COURT MAY.
